Forest Earl Hogarth

INVENTOR.

UNITED STATES PATENT OFFICE.

FOREST EARL HOGARTH, OF SPOKANE, WASHINGTON.

AUTOMATIC SPRING OILER.

1,403,413.

Specification of Letters Patent. Patented Jan. 10, 1922.

Application filed October 13, 1920, Serial No. 416,756. Renewed November 28, 1921. Serial No. 518,494.

To all whom it may concern:

Be it known that I, FOREST EARL HOGARTH, a citizen of the United States, residing at Spokane, in the county of Spokane and 5 State of Washington, have invented certain new and useful Improvements in Automatic Spring Oilers; and I do hereby declare the following to be a full, clear, and exact description of the invention, such as will 10 enable others skilled in the art to which it appertains to make and use the same.

The invention is an automatic device to oil leaf springs of vehicles, especially automobiles, and is accomplished by placing a thick 15 felt pad saturated with oil, and into which is inserted a hollow perforated tube on the top of a leaf spring and around which is wrapped around the pad and the spring an adhesive tape to shut out any dirt or grit 20 from the outside, the workings of the springs while in action automatically distributes the oil inside of the springs and a more detailed description in four figures in an accompanying drawing as follows:

25 Figure I is a perspective view of the portion of the leaf spring on which my improvement is attached.

Figure II is a longitudinal sectional view 30 of the spring showing a sectional view of the improvement with the tape removed and showing the pad and the tube inserted and placed in position.

Figure III is a detail view of the oiling tube with the cap removed.

35 Figure IV is a detail view of the cap of the oiling tube.

In a detail description you will note that the porous pad (10) is applied along the top of the springs (11) and is of sufficient length 40 and width to cover the ends and top of the

leaves (12) of the springs (11). Into this pad is inserted a hollow perforated tube (13) the fitting or oiling end (14) of the tube (13) is bent upwardly so that the same is exposed in the finished state of the im- 45 provements.

The pad, tube and side and top of the springs (11) are then wrapped with adhesive tape (15) with the end of the tube exposed with a cap. Perforations (17) are 50 made in the tube (13) to permit the escape of the oil from the tube (13). The pad (10) becomes saturated with the oil within the same by the movements and actions of the springs (11) and passes downward around 55 the sides and ends of the springs (11) and the springs are kept oiled.

The wrappings (15) excludes from the oil and springs all dirt and grit. If preferred a leather casing may be used in place of 60 tape.

I claim:

1. A spring oiler for use in connection with a leaf spring, comprising a porous padding, applied to the top of the spring 65 and extending toward the ends thereof, and an elongated perforated tube passing longitudinally through the padding and provided with means for filling the same.

2. A spring oiler for use in connection 70 with a leaf spring, comprising a porous padding, applied to the top of the spring and extending toward the ends thereof, and an elongated perforated tube passing longitudinally through the padding and provided 75 with means for filling the same and a covering for the padding tube and the end of the spring such covering composing an adhesive tape wrapped about the padding and spring.

FOREST EARL HOGARTH.
